(54) **BOOT & SHOE SOLES, CUTTING**

(76) Inventor: **Jonathan Hill**

William Hill of Billerica, Massachusetts.

Letters Patent

The Schedule referred to on these Letters Patent and making part of the same containing a description in the words of the grantee, Hill himself of his improvement in the Instrument for cutting Soles and Shoe Toes.

Know all to whom these presents shall come that Jonathan Hill of Billerica in the County of Middlesex and State of Massachusetts, has invented a new, and useful instrument for cutting soles for Boots & Shoes, and that the following is an exact and full description of said Instrument as invented by me. A hoof about eight inches in diameter is made of sheet plate about two inches wide, which being made sharp at one end forming a snufflet, which is bent in such a manner that the edge conforms to the shape of the sole of a Boot. From the back of the knife or cutter at the points, which constitute the heel and the toe of the figure, two arms project parallel to each other an inch or more, one inch wide and one fourth of an inch thick. The arms being placed on a plane horizontal surface of a float of wood the bars of iron one foot in length are placed parallel to each other on the back of the cutter extending lengthwise, one on each side of the two arms which project upward. These bars are drawn toward each other by cords which pass horizontally through both till they project on the two arms. When the cutter is to be used a piece of sole leather is placed on the float of wood and the cutter is placed thereon and may be forced down by an external force, or may be attached by means of the iron bars and strong to the central side of a horse's hoof, such for instance as that described in, *Leather cutter's patent*, Volume 1st page 334. I claim as my invention, the construction of the knife being entire out of one piece and the application of the same to the purpose of cutting soles by means of a horse's hoof.
